UNITED STATES PATENT OFFICE.

HOMER V. HART, OF HAGERSTOWN, MARYLAND, AND CARL F. MASSEY, OF WINCHESTER, VIRGINIA.

LIME-SULFUR MACHINE.

1,205,738.

Specification of Letters Patent. Patented Nov. 21, 1916.

Application filed June 2, 1916. Serial No. 101,347.

To all whom it may concern:

Be it known that we, HOMER V. HART and CARL F. MASSEY, citizens of the United States, and residents of Hagerstown, in the 5 county of Washington and State of Maryland, and Winchester, in the county of Frederick and State of Virginia, respectively, have invented a certain new and useful Improvement in Lime-Sulfur Machines, of 10 which the following is a specification.

Our invention relates to improvements in lime-sulfur machines, and it consists in the combinations, constructions, and arrangements herein described and claimed.

15 An object of the invention is to provide a device which can be economically operated for mixing lime and sulfur to form a spraying compound.

A further object of our invention is to 20 provide a device of the type described which takes up very little room because of the fact that the water heater is located above the mixing tank in a position to receive heat which would otherwise be wasted, this water 25 heater furnishing the necessary supply of water for the mixture.

A further object of our invention is to 30 provide a device of the type described in which the water heater is supported on pipes which constitute a cheap means of constructing 35 the device, and at the same time afford means of conveying water from the heating tank to the mixing tank.

A further object of our invention is to 40 provide an auxiliary sulfur mixer, which may be readily moved to empty its contents into the main mixing tank, and which is provided with a mechanical stirring device.

Other objects and advantages will appear 45 in the following specification, and the novel features of the invention will be particularly pointed out in the appended claims.

Our invention is illustrated in the accompanying drawings forming a part of this 45 application, in which:

Figure 1 is a side view of the machine, the mixing tank being shown in section. Fig. 2 is a sectional view along the line 2—2 of Fig. 1. Fig. 3 is a vertical sectional view 50 along the line 3—3 of Fig. 1. Fig. 4 is a perspective view of a portion of the device, and Fig. 5 is a sectional view along the line 5—5 of Fig. 2.

In carrying out our invention, we provide 55 a main casing 1 which contains a combustion

chamber 2 and an ash pit 3. Disposed in the top of the combustion chamber is a tank 4 which is the main mixing tank, this tank having a semi-cylindrical bottom 4^a.

Running through the tank is a shaft 5, 60 which is disposed concentrically with respect to the bottom 4^a, this shaft being journaled at its ends in bearings 5^a, see Fig. 2.

Rigidly secured to the shaft 5 are arms 6 which bear stirring blades 7. Arms 8 are 65 also secured to the shaft 5, and these arms are secured to segmental members 9 bearing longitudinally arranged cross bars 10 which are preferably made of angle iron and which are arranged to engage the bottom 4^a, as 70 shown in Fig. 3. An arm 11 which projects from the shaft 5, is connected by a pitman 12 with a crank, the latter being attached to a gear 13, which meshes with a pinion 14 on a shaft 15. Mounted on this same shaft 75 15 is a drive pulley 16 which may be connected with a belt 17 or other suitable source of power. The gear 13 is mounted on a shaft 18 which bears a sprocket wheel 19. The latter is connected by a sprocket chain 80 20 with a sprocket wheel 21 on the end of a shaft 22 which extends longitudinally through an auxiliary tank 23, being journaled in the opposite end of the tank in bearings 23^a, see Fig. 1.

Carried by the main casing 1 are four uprights 28 these uprights being in the shape of pipes and being arranged to support a heating tank 29. Secured to the uprights are lugs 25. One end of the shaft 90 22 is journaled in one of these lugs and the other lug forms a bearing for a stub shaft 24, see Fig. 1, which is secured to the end of the tank 23. The tank 23 is therefore pivoted so as to revolve about the axis of 95 the shaft 22.

It will be seen from the drawings that the heating tank 29, as well as the casing 1, bears integral threaded sockets 30 arranged to receive and to retain the ends of the supports 28. One of these supports 28, see Fig. 5, serves as a conduit for permitting flow of water from the upper tank 29 to the lower tank 4, a valve 31 being provided for controlling the flow. At 32 we have shown a 100 cock or faucet which is arranged to extend over the auxiliary tank 23 so as to deliver hot water to the latter tank when desired to do so.

As will be seen from Figs. 1, 3 and 4, a 105

flue 33 communicates at its bottom with the combustion chamber through an opening 33^a, and at its top with the heating space 34, see Fig. 3, underneath the tank 29, through 5 an opening 33^b. The opposite end of the heating space 34 communicates with the stack or chimney 35.

From the foregoing description of the various parts of the device, the operation 10 thereof may be readily understood. The sulfur paste is made in the auxiliary tank 23, while the lime is placed in the main mixing tank 4. In order to fill the mixing tank to the proper depth, it is only necessary to turn the valve 31. The heat from 15 the combustion chamber comes directly on the bottom of the tank 4, while that escaping through the flue 33 tends to heat the water in the tank 29 before the gases finally escape to the chimney or stack 35. Water 20 may be drawn from the faucet 32 into the auxiliary tank 23.

Power is supplied through the belt 17 so 25 that the water and sulfur in the tank 23 are mixed to a paste. At the proper time, depending upon the consistency to which it is desired to bring this paste, the auxiliary tank 23 is inverted, being swung on its pivots and its contents are dumped into 30 the tank 4, which contains the lime and water. Here the mixture of lime and sulfur solution is allowed to boil, and while it is constantly stirred by means of the stirring blades 7, the bottom of the tank being 35 kept in constant agitation by means of the scrapers 10. These parts have an oscillating motion due to the revolution of the crank 13, which transmits movement to the rock shaft 5 through the pitman 12. 40 When the lime-sulfur solution has reached a proper consistency, it may be drawn off through the spout 37.

The device which we have described has 45 several advantages. In the first place, it takes up very little room, since the hot water tank 29 is supported above the main mixing tank 4. The placing of the tank 29 in this position not only secures an economy of room, but it also brings it in position to 50 utilize certain of the waste gases which would otherwise be lost. A third feature of placing the tank in this position is that it is raised so as to supply water, when needed, to the main tank or to the auxiliary 55 tank 23 by the means which have been described.

By hinging the auxiliary tank to the uprights 28, the auxiliary tank is always in position to have the agitating blades 27 60 driven by the sprocket chain 20, and yet the contents of the auxiliary tank may be easily dumped into the main tank.

We claim:

1. In a lime-sulfur machine, a casing having 65 a combustion chamber, a mixing tank

carried by said casing, the bottom of the mixing tank constituting the top of the combustion chamber, means for agitating the contents of the mixing tank and for simultaneously scraping the bottom of the tank, a water heating tank disposed above the mixing tank, and pipes for supporting said water heating tank, one of said pipes constituting a conduit for delivering water from said water heating tank to said mixing tank.

2. In a lime-sulfur machine, a casing having 70 a combustion chamber, a mixing tank carried by said casing, the bottom of the mixing tank constituting the top of the combustion chamber, means for agitating the contents of the mixing tank and for simultaneously scraping the bottom of the tank, a water heating tank disposed above the mixing tank, pipes for supporting said water heating tank, one of said pipes constituting a conduit for delivering water 75 from said water heating tank to said mixing tank, and a flue extending from said combustion chamber beneath said water heating tank for heating the water in said tank.

3. In a lime-sulfur machine, a casing having 80 a combustion chamber, a mixing tank carried by said casing, the bottom of the mixing tank constituting the top of the combustion chamber, uprights carried by said mixing tank, an auxiliary tank hinged to certain of said uprights, an agitator within 85 said mixing tank, an agitator within said auxiliary tank, and a common means for driving said agitators.

4. In a lime-sulfur machine, a casing having 90 a combustion chamber, a mixing tank carried by said casing, the bottom of the mixing tank constituting the top of the combustion chamber, uprights carried by said mixing tank, an auxiliary tank hinged to certain of said uprights, an agitator within 95 said mixing tank, an agitator within said auxiliary tank, a common means for driving said agitators, a water heating tank disposed above said mixing tank, pipes carried by said mixing tank for supporting said water heating tank, one of said pipes constituting a conduit, and means connected 100 with said last named pipes for delivering water either into the mixing tank or into the auxiliary tank, at will.

5. In a lime-sulfur machine, a casing having 105 a combustion chamber, a mixing tank carried by said casing, the bottom of the mixing tank being semi-cylindrical and constituting the top of the combustion chamber, means for agitating the contents of the mixing tank, comprising a rock shaft disposed 110 within the tank, an agitating frame carried by said rock shaft, and a segmental scraping device arranged to engage the bottom of the semi-cylindrical tank and to be moved during 115 the rotation of the rock shaft.

6. In a lime-sulfur machine, a casing having a combustion chamber, a mixing tank carried by said casing, the bottom of the mixing tank being semi-cylindrical and constituting the top of the combustion chamber, means for agitating the contents of the mixing tank comprising a rock shaft disposed within the tank, an agitating frame carried by said rock shaft, a segmental scraping device arranged to engage the bottom of the semi-cylindrical tank and to be moved during the rotation of the rock shaft, power devices carried by said casing for imparting an oscillatory movement to said rock shaft.
- 5 10 15 20 25 30
7. In a lime-sulfur machine, a casing having a combustion chamber, a mixing tank carried by said casing, the bottom of the mixing tank being semi-cylindrical and constituting the top of the combustion chamber.

means for agitating the contents of the mixing tank comprising a rock shaft disposed within the tank, an agitating frame carried by said rock shaft, a segmental scraping device arranged to engage the bottom of the semi-cylindrical tank and to be moved during the rotation of the rock shaft, power devices carried by said casing for imparting an oscillatory movement to said rock shaft, uprights carried by said mixing tank, an auxiliary tank hinged to certain of said uprights, an agitating device disposed within said auxiliary tank consisting of a rotatable shaft provided with agitating blades, and means connected with said power devices for rotating said last named shaft.

HOMER V. HART.
